DESCRIPTION

FIG. 1 is a top, back, and right side perspective view of a communication adapter for endpoint and thin client showing my new design;

FIG. 2 is a back view of FIG. 1 thereof;

FIG. 3 is a front view of FIG. 1 thereof;

FIG. 4 is a side view of FIG. 1 thereof;

FIG. 5 is the opposite side view of FIG. 1 thereof;

FIG. 6 is a top view of FIG. 1 thereof; and,

FIG. 7 is a bottom view of FIG. 1 thereof.

The broken lines throughout the views are for illustrative purposes only and form no part of the claimed design.
